United States Patent Office.

ISAAC P. WENDELL, OF PHILADELPHIA, PENNSYLVANIA.

Letters Patent No. 78,704, dated June 9, 1868; antedated May 23, 1868.

IMPROVEMENT IN LUBRICATING JOURNALS OF CAR-SHAFTS.

The Schedule referred to in these Letters Patent and making part of the same.

TO ALL WHOM IT MAY CONCERN:

Be it known that I, ISAAC P. WENDELL, of the city and county of Philadelphia, and State of Pennsylvania, have invented a new and improved Mode of Lubricating Journals of Car-Shafts, &c.; and I do hereby declare that the following is a full and exact description thereof, reference being had to be accompanying drawings, and to the letters of reference marked thereon.

The nature of my invention mainly consists in the combination of an air-chamber with an oil-distributing plate and connected tube or tubes, so that the pressure of the air in said chamber assists the tubes in supplying the journals of cars or other shafts with oil, the chamber being an additional improvement to the mode of lubricating journals, set forth in my patent, dated January 1, 1867.

In the accompanying drawings, making a part of this specification—

Figure 1 is a plan of the improved device.

Figure 2 is a longitudinal section of the same.

Figure 3 is a cross-section at the red line 1-2 of fig. 1.

Figure 4 is a reverse plan of the oil-distributing plate B, supply-tube C, and air-chamber D, detached from the box A.

Figure 5 is an isometrical view of the oil-box A.

Figure 6 is a plan of a modification of the oil-distributing plate B, supply-tube C, and air-chamber D, arranged in relation to the retaining-plate F.

Figure 7 is a cross-section of the same.

Figure 8 is a side elevation of the said modification, when used without the retaining-plate F.

Figure 9 is a cross-section of the same.

Like letters in all the figures indicate the same parts.

A is an oil-box, which I place in an ordinary car-box. It has a horizontal plate, a, beneath which is an oil-chamber, b. B is an oil-distributing plate, the curved surface, c, of which is of the same radius, or nearly so, as that of the journal which it supplies with oil. From the under side of the plate projects a tube, C, for conveying oil to the curved surface c, as hereinafter described. The tube is surrounded by an air-chamber, D, which projects through the opening d in the plate a of the oil-box A, far enough to cause its lower edges to be always immersed in the oil contained in the chamber b. The under side of the plate B is provided with springs, E, whose resilient parts rest upon the plate a, as seen in figs. 2 and 3, so as to keep the curved face, c, of the former plate, always gently touching the journal to keep up a constant supply of oil. The plate B is provided with inclines e e', running from its curved surface, c, to carry off the surplus oil, there being vertical openings, f f', in the plate, through which the oil descends back into the box A. Above the inclines e e' there are inclines g g', which are auxiliary to the former.

The operation is as follows:

As the journal revolves, it creates a suction up the supply-tube C, causing the oil to ascend, and the air in the air-chamber D, pressing upon the surface of the oil, in the chamber b, assists the flow of oil up the tube to the distributing-plate B. The curved surface, c, of the plate being in contact with the journal, distributes the oil evenly thereon, as the latter revolves. The oil which is not carried around with the journal runs down the inclines e e', and through the vertical openings, f f', back into the oil-box A. The excess of oil that remains on the journal is removed by the scraping-edges h h' of the inclines g g', in the following manner: If the journal runs in the direction of the arrow, the oil will be scraped downwards by the scraper h, and upon the incline e beneath it, and fall through the openings f f' and into the oil-chamber b; and as the journal in its revolutions passes the scraper h', the surplus oil which may not have been scraped off by the scraper h is removed, and runs down the incline g' into the oil-chamber b. Thus a constant supply of oil is kept up to the journal, and the excess removed therefrom, so as to keep its surface clean. The inclines g g' are arranged alike in relation to the inclines e e', so that the journal may run either way, and their action will be the same.

A modification of the device is shown in figs. 6 and 7, in which arrangement an ordinary oil-box is used instead of the box A. The oil-distributing plate B is kept up against the journal by means of the cylindrical spring G, in the circular air-chamber D, the spring resting upon the upper surface of the bottom of the box. The distributing-plate B is retained in its horizontal position each way by means of the plate F, which has an opening, *j*, to receive the air-chamber D. The plate F has flanges, *k k*, which rest upon the upper surface of the bottom of the oil-box.

Figs. 8 and 9 represent another modification of the device, the plate F being dispensed with. In this arrangement the oil-distributing plate B may be retained in its horizontal position by having a loose fit in the oil-box. The spring G may be used either inside or outside of the air-chamber D.

The combination of a spring or springs with the oil-distributing plate for bearing it up against the journal is essentially the same as set forth in my patent, dated October 16, 1866, varying only in detail. The flanges *k*, in both modifications, also prevent the surging of the oil.

What I claim as my invention, and desire to secure by Letters Patent, is—

1. The combination of the air-chamber D with the oil-distributing plate B and supply-tube C, arranged in the oil-box A, or other oil-reservoir, substantially in the manner above described, and for the purpose set forth.
2. The box A, having a division-plate, *a*, and oil-chamber *b* beneath it, in combination with the distributing-plate B, substantially as described and for the purposes specified.
3. The construction of the distributing-plate B, with inclines and scrapers, substantially as described and for the purpose set forth.

In testimony that the above is my invention, I have hereunto set my hand and affixed my seal, this twenty-second day of July, 1867.

ISAAC P. WENDELL. [L. s.]
